CLAIM

The ornamental design for a display screen or portion thereof with animated graphical user interface, as shown and described.

DESCRIPTION

FIG. 1 is a front view of a display screen or portion thereof with graphical user interface, showing my new design; and, FIG. 2 is a second image thereof.

The outermost broken lines illustrate a display screen or portion thereof and form no part of the claimed design. The remaining broken lines illustrate portions of a graphical user interface that form no part of the claimed design.

1 Claim, 2 Drawing Sheets
